UNITED STATES PATENT OFFICE.

ENOCH GEORGE, JR., OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

CAR COUPLING AND DRAFT-YOKE CONNECTION.

1,399,609.

Specification of Letters Patent.

Patented Dec. 6, 1921.

Application filed June 4, 1920. Serial No. 386,607.

To all whom it may concern:

Be it known that I, ENOCH GEORGE, Jr., a citizen of the United States, residing at Pittsburgh, in the county of Allegheny and State of Pennsylvania, have invented certain new and useful Improvements in Car Coupling and Draft-Yoke Connections; and I do hereby declare the following to be a full, clear, and exact description of the invention, such as will enable others skilled in the art to which it appertains to make and use the same.

My invention relates to a car coupler and draft yoke connection for railway draft appliances, and is designed to afford simple, strong and efficient means permitting couplers of the type primarily intended to be connected to the draft yoke without capability of lateral swinging movement to be pivotally connected to the draft yoke so as to be adapted to have such a swinging movement. Generally stated, the preferred embodiment of my invention by which this object is accomplished involves a coupler having a stem, a draft yoke which is provided at its forward end with aligned pivot lugs, and a member intermediate of the coupler and yoke formed with a centrally disposed socket for receiving the rear end of the coupler stem and also provided with spaced slotted arms which receive the coupler stem between them, the rear end of the intermediate member having pivot lugs which mesh with those of the yoke and which are adapted to receive a pivot pin connecting the intermediate member to the yoke, and wedging key means, which extend through the slots of the coupler stem and intermediate member, being provided for attaching the coupler to said intermediate member.

In the drawings illustrating the invention, the scope whereof is pointed out in the claims,—

Figure 1 is a plan view of a draft appliance embodying the invention, the forward end of the coupler and the rear end of the draft yoke being broken away.

Fig. 2 is a side elevation of the construction shown in Fig. 1.

Fig. 3 is a horizontal section on the line 3—3, Fig. 2, the key means being shown in plan.

Fig. 4 is a detail front elevation of a preferred form of means for retaining in as-

sembled position the downwardly removable pivot pin by which the intermediate member is pivotally connected to the yoke.

In the drawings, 1 is the stem of a car coupler and 2 is a draft yoke. The stem 60 of the coupler is provided near its rear end with a transversely extending slot 3 which is adapted to receive key means for connecting the coupler to the intermediate member 4 of the device.

The yoke is provided with longitudinally extending arms 5 which are spaced apart to receive a cushioning unit (not shown) in the well known manner. At their forward ends the arms of the yoke are fashioned with 70 pivot lugs 6 which preferably are formed with flat transversely extending front and rear faces and whose perforations are adapted to receive a vertically extending pivot pin 7. The rear faces 8 of these pivot lugs 75 are adapted to engage the forward end of the cushioning unit carried between the yoke arms 5.

The intermediate member 4 is preferably formed with a centrally disposed forwardly 80 opening socket 9 which receives the rear end of the coupler stem 1, and at its rear end and in horizontal alignment with the socket said intermediate member is also preferably provided with a perforated lug 10 which 85 extends between the pivot lugs 6 of the yoke and whose rear face 11, like the faces 8 of the yoke pivot lugs, is adapted to engage the forward end of the cushioning unit. At the base or inner end of the socket 9 the 90 intermediate member 4 is provided with a wall or face 12 against which the rear end of the coupler stem 1 is adapted to bear, so that buffing shocks received by the car coupler are transmitted therefrom to the cushioning unit directly through the centrally disposed lug 10. In addition to the pivot lug 10 the member 4 is preferably provided at its rear end with pivot lugs 13 which are spaced directly from the lug 10 sufficiently 100 to receive the pivot lug 6 at the forward end of the draft yoke, the rear faces of the intermediate member between the central lug 10 and the outer pivot lugs 13 being beveled to afford clearance for the flat forward face of the pivot lugs 8 of the yoke when the coupler swings laterally. As the

downwardly removable pivot pin 7 extends through the outer pivot lugs 13 as well as through pivot lugs 6 of the yoke and the 110

central pivot lug of the member 4, the pin is placed in quadruple shear and thus offers great resistance to failure.

The intermediate member 4 has at its forward end oppositely disposed spaced arms 14 which receive the coupler stem between them and which have alined slots 15 corresponding to the transversely extending slot 3 of the coupler stem. The coupler stem 1 is connected to the intermediate member 4 through the instrumentality of key means extending through the slots 3 and 15. In order to economize space and thus permit the coupler to have an extended swinging lateral movement, as well as for the purpose of resisting any tendency of the slotted arms 14 to spread or separate when the device is in service, this key means preferably comprises a pair of coacting wedge elements 16 and 17, respectively. The forward wedge 16 is provided at its outer ends with lugs 18 which respectively overlap the outer faces of the slotted arms 14 at their forward ends, while the adjustable wedge 17 is formed at one end with a threaded stem 19 for receiving a nut 20 which bears against the outer face of the adjacent arm 14 of the intermediate member and which by being rotated serves to adjust the position of the wedge 17, thereby forcing the wedge 16 forwardly so as to prevent longitudinal movement of the coupler stem 1 with respect to the intermediate member 4 and at the same time coupling the slotted arms 14 together in a manner resisting their spreading.

As a convenient means for retaining the pivot pin 7 in assembled position, it is preferred to provide the lower pivot lug 13 of the intermediate member with a pair of downwardly extending lugs 21 which are disposed upon opposite sides of the pivot pin opening of the lug 13. Pivottally mounted on the lugs 21 and extending therebetween is a latch bar 22 which is adapted to extend under and support the pivot pin 7. The latch bar 22 has an eccentric portion between its ends by reason of which it normally tends under the influence of gravity to remain in the assembled position illustrated in Fig. 4. In order to provide for the assembly and removal of the latch bar 22, one of the supporting lugs 21 is fashioned with a horizontally extending slot 23 through which the member 22 may be inserted or withdrawn. The companion lug 21 is simply

provided with a circular aperture of suitable size to receive the cylindrical end or pintle of the latch bar 22.

I claim:

1. In a coupler and yoke connection, the combination with a coupler having a stem, of a yoke, a member intermediate of said yoke and coupler provided with spaced arms adapted to receive the stem of said coupler between them, means for pivotally connecting said intermediate member to said yoke, and means for connecting the stem of said coupler to said intermediate member, said last named means being adapted to engage said spaced arms and to resist lateral spreading thereof.

2. In a coupler and yoke connection, the combination with a coupler having a slotted stem, of a draft yoke, a member intermediate of said coupler and yoke and pivotally connected to the latter, and key means for connecting said coupler and intermediate member, said intermediate member being provided at its forward end with oppositely disposed slotted arms adapted to receive the stem of said coupler between them, and said key means comprising a pair of wedge members extending into said slots of said coupler stem and intermediate member, one of said wedge members having lugs which respectively overlap the outer faces of said slotted arms at the forward ends of said arms.

3. In a coupler and yoke connection, the combination with a coupler having a slotted stem, of a draft yoke, a member intermediate of said coupler and yoke and pivotally connected to the latter, and key means for connecting said coupler and intermediate member, said intermediate member being provided at its forward end with oppositely disposed slotted portions adapted to receive the coupler stem between them, and said key means comprising a wedge member extending through said stem and intermediate member and having at its ends forwardly extending lugs embracing the said slotted portions of the intermediate member between them, an adjustable wedge member engaging the rear face of said first named wedge and extending through said coupler stem and intermediate member, and an adjusting nut interposed between said intermediate member and said adjustable wedge.

In testimony whereof I affix my signature.

ENOCH GEORGE, JR.
